UNITED STATES PATENT OFFICE.

OLE F. CARR, OF MEADOW, NEBRASKA.

DESIGN FOR A SIGNAL-LAMP.

44,332.

Specification for Design.

Patented July 15, 1913.

Application filed March 27, 1913. Serial No. 757,245. Term of patent 7 years.

To all whom it may concern:

Be it known that I, OLE F. CARR, a citizen of the United States, residing at Meadow, in the county of Sarpy and State of Nebraska, have invented a new, original, and ornamental Design for Signal-Lamps, of which the following is a specification, reference being had to the accompanying drawing, forming a part thereof.

The single figure of the drawing is a front view of a signal lamp showing my new design.

I claim:

The ornamental design for a signal lamp, as shown.

In testimony whereof I have affixed my signature in presence of two witnesses.

OLE F. CARR.
